SUCTION CLEANER

Wilmer H. Tucker, Canton, Ohio, assignor to The Hoover Company, North Canton, Ohio, a corporation of Ohio

Application February 27, 1933, Serial No. 658,751

6 Claims. (Cl. 15—8)

The present invention relates to suction cleaners in general, and in particular to a new and improved type of suction cleaner embodying a low suction agitator-containing nozzle and a high suction straight-air nozzle.

More specifically the invention comprises a suction cleaner embodying two nozzles, only one of which contains driven surface-agitating means, which are separated by an air tunnel yet are in close proximity so that the agitation produced by the agitating means in the one nozzle is effective to disturb embedded foreign matter in that part of the surface covering contacted by the second nozzle.

It is an object of the present invention to provide a new and improved suction cleaner. It is a further object to provide, in a suction cleaner, a new and novel combination of nozzles and agitating means. A still further object is the provision, in a suction cleaner, of an agitator-containing low suction nozzle and a high suction straight-air nozzle which are separated by an air tunnel. Other and more specific objects will appear upon reading the following specification and claims, and upon considering in connection therewith the attached drawings, to which they relate.

In the drawings, in which the preferred embodiment of the present invention is disclosed:

Figure 1 discloses a suction cleaner embodying the present invention in side elevation, a cross section being shown through the two nozzles and fan chambers;

Figure 2 is a rear view of the cleaner shown in Figure 1;

Figure 3 is a bottom view of the cleaner shown in Figures 1 and 2.

In the drawings illustrating the present invention a low suction agitator-containing nozzle 1 is shown interiorly connected to the fan chamber 2, within which is positioned a suction-creating fan 3. The nozzle 1 is provided with front and rear surface-contacting lips 4 and 5, respectively. In the rear of nozzle 1 is positioned the high suction nozzle 6, which includes extremely thin, surface-contacting lips 8, 8 of a type known as pile-penetrating lips because of their ability to extend between the individual tufts of pile and between the individual fibers of a single tuft. Suction nozzle 6 is interiorly connected to a fan chamber 7, which is positioned adjacent and rearwardly of fan chamber 2 and contains a suction-creating fan 9. Fans 3 and 9 are each mounted upon the motor shaft 11 which extends forwardly from the motor 10

thru the two fan chambers and into the forward nozzle 1 where it is provided with a pulley 12.

Within the low suction nozzle 1 is positioned a rotatable agitator 14 of a common and well-known type which includes rigid beating elements 15, 15 and a brush 16. Between its ends the agitator 14 is formed as a pulley surface and between this surface and the pulley 12, carried by motor shaft 10, is positioned a belt 17, which functions to drive the agitator upon the rotation of the shaft.

The fan chambers 2 and 7 are provided with adjacent exhaust outlets 18 and 19, respectively, which open into bags 20 and 21 of air-pervious material which permits the air to pass therethrough while retaining the foreign matter carried thereby.

As in the usual suction cleaners, front supporting wheels 22, 22 are provided which are carried by a supporting shaft 23, there being 75 means, indicated generally by the reference character 24, by which the wheels can be adjusted vertically relative to the cleaner for the purpose of raising and lowering the nozzles 1 and 6 with respect to the covering undergoing cleaning. 80 Rear supporting wheels 25, 25 are attached to the motor 11 and together with the front supporting wheels, make it possible for the operator to easily move the cleaner over the surface covering undergoing cleaning, there being a pivoted handle 85 26 provided through which the moving force can be exerted.

In the suction cleaner constructed in accordance with the present invention the nozzles 1 and 6 are spaced as is clearly indicated in Figures 1 and 3. The space between the rear lip 5 of the nozzle 1 and the front lip 8 of the nozzle 6 is of such dimensions that an air tunnel is formed between the two nozzles of such size that sufficient air can pass therethru to supply the suction effective along the entire length of lips 5 and 8. As is clearly seen in Figure 3, this tunnel, which is indicated by the reference character 27, is interiorly connected to atmosphere through openings 28, 28.

In the operation of the suction cleaner constructed in accordance with the present invention, upon the rotation of the motor shaft 10 a negative pressure or suction is created within the nozzles 1 and 6 by the rotating fans 3 and 9, which draw air from the nozzles into fan chambers 2 and 7, and exhaust it into the bags 20 and 21. In response to the suction within the two nozzles the surface covering thereunder is lifted upwardly and into contact with the nozzle 11.

lips. Within the nozzle 1 the agitator 14, rotated by its driving belt 17, positively agitates, brushes, and vibrates the suspended surface covering, not only between the nozzle lips 4 and 5, but effectively between the front lip 4 and rear lip 8, so that that part of the covering between the lips 8 and 8 is disturbed. The suction within the nozzle 1 is preferably lower than that within the nozzle 6. To this end fan 3 is of smaller diameter than fan 9. Fan 3 handles the greater volume of air, however, and is therefore wider than fan 9. A relatively low suction is desired within the nozzle 1 for with a greater suction, such as that desired within the nozzle 6, the surface covering would be lifted against the agitator body with undue force, resulting in an excessive load upon the driving motor. In the nozzle 6, however, no restrictions as to suction need be made and the suction of that nozzle is considerably higher than the suction within the nozzle 1, and this fact, coupled with the covering vibration resulting from the agitator within the nozzle 1, results in effective cleaning by the nozzle 6. The positioning of the air tunnel 27 between the two nozzles makes possible the entrance of cleaning air under the entire length of lips 5 and 8, thereby resulting in greater cleaning effectiveness. If the air tunnel were omitted the high suction in the nozzle 6 would function to draw dirt-laden air under the common lip from the nozzle 1, a clearly undesirable relationship.

I claim:

1. In a suction cleaner, a high-suction nozzle, a low-suction nozzle, said nozzles being arranged to clean the same covering portions upon cleaner movement, suction-creating means connected to said nozzles, a space open to atmosphere between said nozzles adapted to convey air along the lengths thereof, means spacing the surface-contacting portions of said nozzles above a surface covering undergoing cleaning, said nozzles being so spaced that the surface covering undergoing cleaning is lifted from the front lip of the forward nozzle to the rear lip of the rear nozzle by the suction in the two nozzles.
2. In a suction cleaner, a high-suction nozzle, a low-suction nozzle, said nozzles arranged one behind the other, suction-creating means connected to said nozzles, an agitator in said low-suction nozzle, a space open to atmosphere between said nozzles adapted to convey air to the adjacent nozzles, means spacing the surface-con-

tacting portions of said nozzles above a surface covering undergoing cleaning, the said nozzles being so spaced that the surface covering undergoing cleaning is lifted from the front lip of the forward nozzle to the rear lip of the rear nozzle by the suction in the two nozzles.

3. In a suction cleaner, a high-suction nozzle, a low-suction nozzle, said nozzles arranged one behind the other, suction-creating means connected to said nozzles, a space open to atmosphere extending between said nozzles, a rigid agitator in said low-suction nozzle, means to actuate said agitator to vibrate a surface covering undergoing cleaning, said nozzles being so arranged and spaced that the covering is lifted from the front lip of the forward nozzle to the rear lip of the rear nozzle by the suction in the two nozzles.

4. In a suction cleaner, a low-suction nozzle, a high-suction nozzle, said nozzles arranged one behind the other, a space open to atmosphere between said nozzles, means supporting said nozzles above a surface covering undergoing cleaning, said nozzles being so arranged that the covering is lifted from the front lip of the forward nozzle to the rear lip of the rear nozzle by the suction in the two nozzles, and means to vibrate the lifted portion of the covering.

5. In a suction cleaner, a nozzle, a second nozzle, said nozzles arranged one behind the other, suction-creating means connected to said nozzles, an agitator in said first nozzle, a space open to atmosphere between said nozzles adapted to convey air to the adjacent nozzles, means spacing the surface-contacting portions of said nozzles above a surface covering undergoing cleaning, the said nozzles being so spaced that the surface covering undergoing cleaning is lifted from the front lip of the forward nozzle to the rear lip of the rear nozzle by the suction in the two nozzles.

6. In a suction cleaner, a high-suction nozzle, a low-suction nozzle, said nozzles arranged one behind the other, suction-creating means connected to said nozzles, a space open to atmosphere between said nozzles adapted to convey air to the adjacent nozzles, means spacing the surface-contacting portions of said nozzles above a surface covering undergoing cleaning, the said nozzles being so spaced that the surface covering undergoing cleaning is lifted from the front lip of the forward nozzle to the rear lip of the rear nozzle by the suction in the two nozzles.
